UNITED STATES PATENT OFFICE.

THOMAS R. BROWN, OF WILMERDING, PENNSYLVANIA, ASSIGNOR OF
TWO-THIRDS TO WILLIAM C. DALLAS, OF ST. LOUIS, MISSOURI, AND
J. S. SEELEY AND EDWARD McVICKER, OF FRANKLIN, PENNSYLVANIA.

AUTOMATIC GRAVITY-FEED LUBRICATOR.

SPECIFICATION forming part of Letters Patent No. 712,254, dated October 28, 1902.

Application filed August 16, 1901. Serial No. 72,304. (No model.)

To all whom it may concern:

Be it known that I, THOMAS R. BROWN, a citizen of the United States, residing at Wilmerding, in the county of Allegheny and State 5 of Pennsylvania, have invented certain new and useful Improvements in Automatic Gravity-Feed Lubricators, of which the following is a specification, reference being had therein to the accompanying drawings.

10 My invention relates to lubricators, and has for its objects to provide a dash-feed automatic cut-off oil-cup adapted for use on main rods, driving-shafts, and other movable parts of locomotives and other machinery, provided 15 with means to effectually catch and retain in a reservoir-receptacle the oil fed from the cup by the agitation thereof, provided with means to secure a uniform feed of oil, and to generally simplify and strengthen the construction of a lubricator of this class.

20 To these ends my invention consists of the device hereinafter described and claimed.

In the accompanying drawings, which illustrate my invention, Figure 1 is a central vertical section of an oil-cup embodying my invention; Figs. 2, 3, and 4, similar views of modified forms of the device.

Referring to the drawings, A, Fig. 1, is the cap or plug of the lubricator, which is provided with a head for engagement by a wrench 30 and with screw-threads to engage the body B of the cup. Seated in the neck of the body portion below the plug is a strainer S, which is adapted to protect the entrance to the cup from cinders and other foreign matter when 35 the plug is removed. Extending downwardly from the body of the cup, within the same, is a circumferential guide-wall or hood B'.

The body B of the cup is preferably made 40 of brass and at its lower end is provided with a screw-threaded flange b, which screws within a corresponding flange on a base portion C. This base is made of malleable iron or crucible-steel in order to obtain sufficient strength. With this difference in metals of the body portion and the base it is possible that, should the shaft become heated and heat the base, owing to the difference in the coefficients of expansion of the respective parts,

the body would be caused to expand more 50 than the base. To prevent this expansion from loosening the joint between body and base, the former is screwed within the base, as described, whereby on expansion the body would expand against the base, and thereby 55 maintain a tight joint. The stud C² of base C is exteriorly screw-threaded to permit of attachment of the cup to the rod or shaft.

A stem C³ rises from the interior of the base C to near the upper part of the cup, where it 60 is provided with a flaring receptacle C', having a reversely-curved lip H. A passage E E' is formed in this stem and is continued through the stud C². The passage is made larger than necessary for the proper feed in 65 order to provide a range of reduction at F, where the passage is reduced to the size proper to provide a proper amount of oil. This reduction-check F is purposely located at a distance from the bottom of the cup, so that it 70 cannot be enlarged or tampered with, the opening of passage E' being so small that no ordinary tool can be inserted.

In the inner receptacle and reservoir C' is placed a valve-ball D, which when the rod 75 and lubricator are at rest is caused by the sloping bottom of the receptacle to roll to the center of the same, and thus close the entrance to the passage E and cut off the feed of oil to the rod. The guide or hood B' is 80 adapted to extend down and inclose the ball and serves to limit the movement thereof upon its seat.

The transverse diameter of the body B is made greater than the height in order to effectually feed out all the oil contained in the cup. 85

One practical advantage of having the mouth of the inner flaring cup C' open is to prevent clogging, which may occur in cases 90 where cups have small perforations for admission of the oil. With the open mouth free access to the receptacle is afforded, and a sufficient flow of oil is not only always insured around the dependent hood B', which extends 95 down to the ball when such hood is used, but by the function of the reversed curved lip H such greater supply is retained instead of be-

- ing thrown out or back into the outer cup, as is apt to be the case with open shallow saucers after the supply in the outer cup has been entirely or nearly exhausted.
- 5 The operation of the device is as follows: The agitation of the cup by the movement of the rod will cause the oil to surge and rush over the lip of the receptacle, which offers a much larger surface for catching the oil than 10 the usual plain stem of other devices of this class. The motion also unseats the valve-ball and permits the oil to enter the passage, whence it will be fed through the tube to the rod or shaft, the reduced portion F serving 15 to check the flow to the required amount. The guide or hood B' limits the lateral movement of the ball and can be of such size as to provide an easy rolling motion for the ball when the speed of the rod is not sufficient to 20 lift the ball in a vertical direction away from the seat. This provides a feed of oil when starting the rod. When the engine or other machinery stops, the ball will lodge in the seat over the passage and stop all flow of oil 25 from the receptacle. On the stoppage of the engine it will be found that the inner lip H has prevented the escape of all the oil from the inner cup, which will contain enough oil to lubricate the rod upon starting.
- 30 In Fig. 2 a form of lubricator is shown in which in place of the guide B' of Fig. 1, made integral with the body of the cup, the plug A is provided with a guide or hood B², which is adapted to fit over and inclose the ball-valve.
- 35 In Fig. 3 another form of cup is shown in which a cap or lid G is provided and in which the saucer-receptacle C⁴ and a hood or guide B³ form part of said lid.
- 40 In Fig. 4 a form of lubricator is shown especially adapted for rods of slow speeds. The guide or hood to limit the movement of the ball is dispensed with, and the receptacle C⁵ is made deeper and with a greater angle of 45 slope toward the center than in the other forms. In this construction at slow speeds the ball will roll back and forth more or less from its seat and produce a feeding action similar to that in the devices of Figs. 1 to 3,
- 50 or when the engine reaches a sufficient speed the ball will hug the sides of the saucer and have a circular movement, following the inside curved portion of the inner cup as though on a track, in this way leaving the opening

to the oil-passage continuously open while the 55 speed is maintained and providing practically a constant feed to the rod. The angle or pitch of the bottom of the saucer is such that at the greatest angle which the cup may assume in the stopping of the engine the ball will roll in 60 its seat and secure the cup from any waste of oil.

Having thus described my invention, what I claim is—

1. A dash-feed lubricator comprising in 65 combination an outer oil-cup, an interior stem arising from the base of the oil-cup provided with a central oil-channel and terminating at its upper end in an imperforate flaring cup-shaped receptacle having a central uncovered 70 opening at its top and a reversed lip extending around said opening, substantially as described.

2. In a dash-feed lubricator, an outer oil-containing cup, an inner tubular feed-stem 75 rising from the base of said cup, an inner open oil-catching receptacle at the upper end of said stem, having a contracted open mouth consisting of a reversed lip and central opening in line with but below the mouth of the 80 outer cup, said outer cup made of greater transverse diameter than height, substantially as described.

3. In a lubricator, a tubular stem terminating at the upper end in an open receptacle, 85 said receptacle having a ball-seating center portion, a wide circumferential base portion sloping up from the center of the stem and having a turned-in lip forming an annular groove and a way for the ball, and a ball-valve in said receptacle, substantially as described.

4. In an automatic gravity-feed lubricator, an outer oil-containing cup, an oil-feed stem, an inner receptacle at the upper end of the 95 stem, having a valve-seat, and a wide base portion extending around said seat, a ball in said receptacle, a closure member for said outer cup and a guide-wall depending from said member above said receptacle to inclose 100 and guide said ball, substantially as described.

In testimony whereof I affix my signature in presence of two witnesses.

THOMAS R. BROWN.
